[57] **ABSTRACT**

A number of mono- and poly- substituted s-triazolo-[3,4-a]-isoquinolines are shown to have antiinflammatory/analgesic activity, and, in some instances, are additionally shown to have anti-secretory activity. The 3-trifluoromethyl derivative is preferred.

FIG. 2

**METHODS FOR REDUCING INFLAMMATORY
REACTIONS USING CERTAIN
S-TRIAZOLO-(3,4-a)-ISOQUINOLINES**

This is a continuation of application Ser. No. 140,198, filed May 4, 1971, now abandoned.

BACKGROUND OF THE INVENTION

The present invention relates to the drug field, and more particularly to methods and pharmaceutical compositions for treating mammals utilizing as active agents certain synthetic organic heterocyclic compounds from the class known as s-triazolo-[3,4-a]-isoquinolines.

The preparation of various s-triazolo-[3,4-a]-isoquinolines is disclosed by (1) S. Naqui et al., *Indian J. Chem.*, 3, 162-4 (1965); (2) G. S. Sidhu et al., *Jour. Heterocyclic Chem.*, 3, 158-164 (1966); (3) J. E. Francis, U.S. Pat. No. 3,354,164 (1967); (4) H. K. Reimlinger et al., French Pat. No. 1,573,135 (1969) and (5) H. K. Reimlinger et al., *Chem. Ber.* 103, 1960-1981 (1970).

No pharmaceutical compositions or utility are disclosed in references (1), (2), (4) and (5) cited above. Francis (3) discloses that unsubstituted s-triazolo-[3,4-a]-isoquinoline and its 3-lower alkyl derivatives are coronary vasodilators.

The invention is particularly concerned with the treatment of inflammatory disorders, among which are the conditions known as arthritis.

The term "arthritis" is applied to a group of related disorders of the joints which are characterized by pain, inflammation and stiffness. Certain types of arthritis are due to specific infectious agents, but no specific cause is known for the most common type, known as rheumatoid arthritis. While this is primarily an inflammatory disease of the joints, it is sometimes accompanied by pedal edema, that is, an accumulation of fluid in the tissues of the foot. Treatment of this disease involves the administration of agents which have been found effective in reducing the pain and the inflammation. Such agents have come to be generally known as anti-inflammatory agents.

Chemical compounds having structures of varying complexity, from the structurally simple aspirin to relatively complex steroid compounds, are known to be useful anti-inflammatory agents in the treatment of arthritic and related disorders in man and other mammals. Among such recognized anti-inflammatory agents, in addition to aspirin, are the following, to which reference may be conveniently made in the Merck Index, 8th Ed., Merck & Co., Rahway, N. J. (1968): dexamethasone (p. 334), hydrocortisone (p. 542) indomethacin (p. 566), mefenamic acid (p. 648) and phenylbutazone (p. 815). No s-triazolo-[3,4-a]-isoquinolines are among the compounds which have heretofore been recognized as having anti-inflammatory activity.

Detection of anti-inflammatory activity is a relatively difficult matter. Many unsuccessful attempts have been made to produce a disease in experimental animals analogous to rheumatoid arthritis. Several procedures have been developed, utilizing induced disorders in animals, to evaluate anti-inflammatory activity on a comparative basis. Among the established procedures for this purpose are the following:

1. Inhibition of Carrageenin-Induced Pedal Edema — Winter et al., *Proc. Soc. Exptl. Biol. Med.* 111: 544

(1962). After administration of the drug a solution of carrageenin is injected into the left hind paw of the test animal, and the volume of edema is calculated from the increase in volume of the paw.

- 5 2. Inhibition of Cotton Pellet Granuloma — Meier et al., *Experientia* 6: 469 (1950). A sterile cotton disc is implanted subcutaneously into a rat, with concurrent oral administration of the drug twice daily for four days. The inflammation due to the presence of the cotton causes formation of a granuloma. Five days after implantation the pellet and granuloma are removed. The increment of dry weight is taken as the measure of granuloma formation.
- 10 3. Inhibition of Thermal Edema — Rocha e Silva et al., *Med. Exp.* 3: 371 (1960). The drug is administered orally to a rat prior to immersion of the left hind paw in water at 55°C. for 30 seconds. Edema caused by the heat increases the paw volume, which is measured at intervals.
- 15 20 4. Freund's Adjuvant Studies — (See generally Newbould, *Brit. J. Pharmacol.* 21: 127 (1963). The drug is administered orally, in accordance with the procedure described hereinafter, to combat the arthriticlike syndrome produced by injection of *Mycobacterium butyricum* (Freund's adjuvant).

Just as the inflammation of rheumatoid arthritis is accompanied by pain, it has been observed that anti-inflammatory activity is frequently closely associated with analgesic (pain-relieving) activity.

- 25 30 Complementing the test procedures outlined above, a corresponding group of animal tests to assess analgesic activity has also been developed. These include the following:

1. Pressure-Pain Method — Randall and Selitto, *Arch. Int. Pharmacodyn.* 111: 409 (1957). Rats are injected in the left hind paw with a suspension of brewer's yeast. This causes an inflammation which increases the sensitivity to pain caused by pressure on the foot. This sensitivity can be modified by analgesic agents.
- 35 40 2. Anti-Writhing — Vander Wende et al., *Fed. Proc.* 15: 494 (1956). Intraperitoneal injection of phenyl-p-quinone in mice cause acute abdominal pain characterized by numerous writhing episodes (contraction and torsion of the abdomen). Administration of an analgesic prior to the administration of the phenyl-p-quinone modifies the number of writhing episodes occurring within a standard time interval, and this is used as an index of analgesic potency.

- 45 50 3. Rat Tail Flick — D'Amour and Smith, *J. Pharmacol. Exptl. Therap.* 72: 74 (1941). Differences in the sensitivity of a rat's tail to heat before and after drug administration is utilized as an index of analgesic potency.

SUMMARY OF THE INVENTION

Among the several objects of the invention may be noted the provision of useful pharmaceutical compositions and methods for combatting an inflammatory reaction in a susceptible mammal; the provision of such compositions and methods which involve the use of certain s-triazolo-[3,4-a]-isoquinoline compounds; the provision of compositions of the character indicated which exhibit anti-inflammatory/analgesic activity and which, in some instances, additionally exhibit anti-secretory activity; and the provision of such compositions which are adapted for either oral or parenteral administration to mammals susceptible to inflammatory

reactions. Other objects and features of the invention will be in part apparent and in part pointed out hereinafter.

The present invention is thus directed to a method of combatting an inflammatory reaction in a susceptible mammal which comprises administering to said mammal an effective amount of an s-triazolo-[3,4-a]-isoquinoline compound from the group hereinafter specifically set forth. The invention is also directed to pharmaceutical compositions comprising such a compound and a pharmaceutical carrier.

BRIEF DESCRIPTION OF THE DRAWING

FIG. 1 is a graphical representation showing the effect of 3-trifluoromethyl-s-triazolo-[3,4-a]-isoquinoline on adjuvant-induced polyarthritis; and

FIG. 2 is a graphical representation showing the analgesic activity of 3-trifluoromethyl-s-triazolo-[3,4-a]-isoquinoline and other agents on yeast inflamed rat paws.

DESCRIPTION OF THE PREFERRED EMBODIMENTS

In accordance with the present invention, it has now been found that certain s-triazolo-[3,4-a]-isoquinoline compounds are useful anti-inflammatory agents. In this series of compounds, anti-inflammatory activity has been found to be quite selective. In other words, the presence or absence of such activity, and its degree when present, is quite sensitive to the position and type of substitution on the basic s-triazolo-[3,4-a]-isoquinoline structure.

The specific s-triazolo-[3,4-a]-isoquinoline compounds which have been found to possess anti-inflammatory activity are:

- 3-trifluoromethyl-s-triazolo-[3,4-a]-isoquinoline
  - 6-chloro-s-triazolo-[3,4-a]-isoquinoline
  - 3-(N-morpholinylmethyl)s-triazolo-[3,4-a]-isoquinoline
  - 5-chloro-s-triazolo-[3,4-a]-isoquinoline
  - 7-nitro-s-triazolo-[3,4-a]-isoquinoline
  - 6-cyano-s-triazolo-[3,4-a]-isoquinoline
  - 7-chloro-s-triazolo-[3,4-a]-isoquinoline
  - 6-bromo-s-triazolo-[3,4-a]-isoquinoline
  - 6-methoxy-s-triazolo-[3,4-a]-isoquinoline
  - 7-nitro-3-trifluoromethyl-s-triazolo-[3,4-a]-isoquinoline
  - 3-chloro-s-triazolo-[3,4-a]-isoquinoline
  - 3,6-dichloro-s-triazolo-[3,4-a]-isoquinoline
  - 3-styryl-s-triazolo-[3,4-a]-isoquinoline
  - 3-methylthio-s-triazolo-[3,4-a]-isoquinoline
  - 3-methyl-6-chloro-s-triazolo-[3,4-a]-isoquinoline
  - 3-ethylthio-s-triazolo-[3,4-a]-isoquinoline
  - 8-methoxy-s-triazolo-[3,4-a]-isoquinoline
  - 6-chloro-3-isopropyl-s-triazolo-[3,4-a]-isoquinoline
  - 3-methyl-6-bromo-s-triazolo-[3,4-a]-isoquinoline
  - 7-bromo-s-triazolo-[3,4-a]-isoquinoline
  - 3-bromo-s-triazolo-[3,4-a]-isoquinoline
  - 3-phenyl-s-triazolo-[3,4-a]-isoquinoline
  - 3-methyl-s-triazolo-[3,4-a]-isoquinoline
  - s-triazolo-[3,4-a]-isoquinoline
  - 3-oxo-s-triazolo-[3,4-a]-isoquinoline
  - (s-triazolo-[3,4-a]-isoquinoline-3(2H)-one)
  - 3-thioxo-s-triazolo-[3,4-a]-isoquinoline
  - (s-triazolo-[3,4-a]-isoquinoline-3(2H)-thione)
- and the pharmaceutically acceptable, nontoxic acid addition salts thereof. Such addition salts may be de-

rived from hydrochloric acid, hydrobromic acid, phosphoric acid, methanesulfonic acid and the like.

Homologous compounds, such as 3-ethyl-s-triazolo-[3,4-a]-isoquinoline, 6-chloro-3-ethyl-s-triazolo-[3,4-a]-isoquinoline and 6-bromo-3-isobutyl-s-triazolo-[3,4-a]-isoquinoline and the aforementioned salts thereof, also possess anti-inflammatory activity.

Consistent with previous knowledge, in many of the above-noted compounds, analgesic activity is desirably associated with the anti-inflammatory activity. Further, certain of the compounds (e.g., 3-trifluoromethyl-s-triazolo-[3,4-a]-isoquinoline, 6-chloro-s-triazolo-[3,4-a]-isoquinoline, 7-nitro-s-triazolo-[3,4-a]-isoquinoline, 3-methylthio-s-triazolo-[3,4-a]-isoquinoline and 3-ethylthio-s-triazolo-[3,4-a]-isoquinoline) advantageously exhibit anti-secretory activity rather than the ulcerogenic properties exhibited by certain prior art anti-inflammatory agents, such as the cortical steroids.

20 In the preferred embodiment of the invention, 3-trifluoromethyl-s-triazolo-[3,4-a]-isoquinoline is employed as an anti-inflammatory agent. As will appear from the detailed test results set forth hereinafter, this compound is an effective anti-inflammatory/analgesic agent active in a variety of pharmacologic procedures. Summarizing its properties, this compound is effective against carrageenin-induced pedal edema in both intact and adrenalectomized rats and in guinea pigs. In other animals, the compound shows activity in the cotton-pellet granuloma assay in both intact and adrenalectomized rats, appears capable of inhibiting the onset of thermally-induced edema, and is active locally while being devoid of counterirritant effects. The compound significantly inhibits adjuvant-induced polyarthritis. It 25 does not produce thymolysis, adrenal hypertrophy or gastric irritation. Further, it reduces yeast-induced fever in rats, phenylquinone-induced writhing in mice, and elevates yeast-induced pain threshold in rats. The compound causes little or no gross pharmacological 30 symptoms in higher species (dog, monkey) and appears devoid of serious autonomic and cardiovascular effects. In lethality studies, the compound shows a higher therapeutic safety margin than any of the standard reference agents tested. Finally, the compound appears 35 non-anticholinergic and significantly reduces gastric acid secretion by several routes of administration utilizing the pyloric-ligated rat procedure.

In accordance with the invention, pharmaceutical compositions therapeutically useful for combatting inflammatory reactions in susceptible mammals are provided and comprise an aforementioned s-triazolo-[3,4-a]-isoquinoline compound and a pharmaceutical carrier which may be either liquid or solid material. These 40 compositions may be administered orally or parenterally in the usual pharmaceutical forms including capsules, tablets, solutions, suspensions and the like. For example, the s-triazolo-[3,4-a]-isoquinoline compound may be formulated with carriers such as magnesium stearate and lactose and filled into gelatin capsules. Examples of other solid pharmaceutical carriers, such as fillers, binders and lubricants, include dibasic calcium phosphate, calcium sulfate dihydrate, microcrystalline cellulose, calcium carbonate and talc. The pharmaceutical compositions of the invention may also be in the 45 form of sterile parenteral solutions with the s-triazolo-[3,4-a]-isoquinoline compound dissolved in a sterile parenteral solvent such as polyethylene glycol, propy-

lene glycol, water or mixtures of solvents or the compositions may be in the form of suspensions.

Where the s-triazolo-[3,4-a]-isoquinoline compound is water-insoluble (e.g., 3-trifluoromethyl-s-triazolo-[3,4-a]-isoquinoline), it is preferred that the compound be formulated into the pharmaceutical compositions of the invention in a micronized form, as by milling the compound by conventional methods. More particularly, it is preferred that the compound be micronized to a particle size of approximately 1-10 microns.

The following examples illustrate the invention:

EXAMPLE 1

3-Trifluoromethyl-s-triazolo-[3,4-a]-isoquinoline (hereinafter designated NC-1140) (French patent No. 1,573,135) was milled to pass a No. 325 U.S. Standard Sieve. The milled product (100 g.) was thoroughly blended with magnesium stearate (2 g.) and lactose (298 g.). Size No. 1 gelatin capsules (1000) were filled with the mixture. Each capsule contained 100 mg. of NC-1140.

Similarly, capsules containing 10, 25, 37.5, 50 and 200 mg. of NC-1140, respectively, were prepared.

In the formula described above, the lactose may be wholly or partially replaced by any of the following: dibasic calcium phosphate, calcium sulfate dihydrate, microcrystalline cellulose, calcium carbonate, or talc.

For studies in mice, rats and guinea pigs, aqueous suspensions containing the desired dose of finely milled (-325 mesh) NC-1140 and 0.25 percent methylcellulose were prepared. A similar preparation containing NC-1140 (20 mg./ml.) and methylcellulose (0.5 percent W/V) was prepared and used for studies in monkeys.

NC-1140 is a white, crystalline material which is insoluble in water. Unlike a majority of non-steroid anti-inflammatory agents, NC-1140 has no acidic function. For most of the animal studies described below, the compound was utilized in a micronized form (particle size 1-10 μ) and administered as a finely divided suspension in a 0.25 percent methylcellulose solution to mice, rats, and guinea pigs. Rats (male Wistar, 100 to 175 grams) and mongrel dogs of both sexes were fasted for approximately 18 hours prior to use. The compound was administered orally in capsules to dogs. Monkeys were given the agent by intubation utilizing a 0.5 percent methylcellulose vehicle. For pharmacodynamic and autonomic studies in cats and dogs, NC-1140 was dissolved in polyethylene glycol 200 or 400.

EXAMPLE 2

Anti-Inflammatory Activity of NC-1140

A. Inhibition of Carrageenin-Induced Pedal Edema (Rats)

The procedure used for measuring inhibition of carrageenin-induced edema was a modification of the method of Winter et al., Proc. Soc. Exptl. Biol. Med. 111: 544 (1962). The device used for measurement of the paw volume was an adaptation of the water displacement procedure described by Adamkiewicz et al., Can. J. Biochem. Physiol. 33: 332 (1955). NC-1140 was studied and compared with selected anti-inflammatory drugs in preventing the edema caused by the intraplantar injection of 0.05 ml. of a sterile 1.0 percent solution of carrageenin. All drugs were administered (orally or intraperitoneally) 1 hour prior to the injection of the phlogistic substance into the left hind paw of rats. At peak swelling time (3 hours), the volume of edema was calculated by differential paw vol-

umes. The ED_{50} value was obtained for each drug and is defined as that dose which reduced edema formation by 25 percent or more compared with the mean control response (parallel run) in 50 percent of the animals. The following results were obtained:

Table 1

Drug	Effect of Selected Anti-inflammatory Agents on Carrageenin-Induced Paw Edema (Rats)			
	ED ₅₀ , mg./kg. (95% Confidence Limits)	Oral	I.P.	
Aspirin	224	(102-490)	16	(10-26)
Phenylbutazone	30	(14-62)	9.8	(5.4-17.6)
Hydrocortisone Acetate	26	(13-55)	9.3	(5.6-15.5)
NC-1140	21	(11-40)	11.2	(6.1-20.7)
Indomethacin	2.4	(1.1-4.9)	0.5	(0.4-0.7)
Dexamethasone	0.18	(0.16-0.20)	0.11	(0.07-0.18)

Thus, NC-1140 is approximately equipotent, on a mg./kg. basis, as phenylbutazone and hydrocortisone acetate by both oral and intraperitoneal routes of administration.

B. Effect of NC-1140 on Reducing Established Edema

Investigations were also conducted to ascertain the effects of NC-1140 and several standard reference agents on reducing previously established carrageenin-produced rat paw edema. This particular test infers therapy rather than prevention. In this procedure the drugs were not administered until peak edema was manifest in the paw (3 hours post carrageenin). Thereupon measurements of paw volumes were made 1 and 3 hours post drug.

Table 2

Drug	Effect of Various Agents on Reducing Established Edema		
	Oral Dose (mg./kg.)	% Reduction in Established Edema 1 hour	3 hours
Aspirin	25	0	0
	50	0	26
	100	0	42**
	200	0	64**
NC-1140	25	33**	56**
	50	39**	70**
	100	37**	69**
	200	29*	66**
Phenylbutazone	10	17*	0
	20	16	17
	40	15	19
	80	24*	32**
Hydrocortisone Acetate	5	0	0
	10	1	10
	20	3	17*
	40	12	28**
Dexamethasone	0.5	0	3
	1	0	0
	2	0	12
	4	0	16*
Mefenamic Acid	10	3	0
	20	0	0
	40	15*	6
	80	0	0
Indomethacin	0.3	0	0
	1	0	0
	3	0	0
	10	0	0

*P ≤ .05

**P ≤ .01

The data indicate that NC-1140, aspirin, phenylbutazone, hydrocortisone acetate, and, to a lesser extent, dexamethasone were capable of reducing previously established rat hind paw edema induced by carrageenin. Both mefenamic acid and indomethacin showed little or no activity in this procedure. NC-1140, at all dose levels tested, appears far more effective at

both the one and three hour measurements than any of the other agents studied.

C. Inhibition of Carrageein-Produced Edema (Guinea Pigs)

To demonstrate anti-inflammatory activity in another species, inhibition of carrageein-produced pedal edema was also studied in guinea pigs at selected dose levels with several representative compounds. The results given in the following table indicate that NC-1140, phenylbutazone, and, to a lesser extent, indomethacin, at the doses studied, were active in this species.

Table 3

Inhibition of Carrageein-Induced Pedal Edema (Guinea Pigs)			
Drug	Oral Dose (mg./kg.)	Paw Edema (ml.)	Reduction of Edema
Methylcellulose	(Controls)	0.62	—
Aspirin	200	0.51	18%
NC-1140	100	0.31	50%*
Phenylbutazone	100	0.17	73%**
Indomethacin	10	0.37	40%
Dexamethasone	1	0.54	13%

*P<.05

**P<.01

D. Cotton Pellet Granuloma

Inhibition of granuloma formation was determined by a modification of the method of Meier et al., *Experientia* 6: 469 (1950). Essentially it consisted of the subcutaneous implantation of a sterile cotton disc into either intact or adrenalectomized rats with concomitant oral administration of drug twice daily for four days. Removal of the pellets along with the granuloma formation after five days was performed and the increment in dry weight considered as the measure of granuloma formation. Based on several studies, a 40 percent reduction in granuloma formation was considered significant. Table 4 shows the ED₅₀ values obtained with NC-1140 and several standard reference agents.

The results indicated that anti-inflammatory activity can be displayed in both normal and adrenalectomized rats. This implied that the anti-inflammatory activity of NC-1140 was not caused by the release of endogenous adrenocortical steroids.

Table 4

Effect of Various Anti-Inflammatory Agents in the Cotton Pellet Granuloma Procedure		
Drug	ED ₅₀ vs. Cotton Pellet (mg./kg. - 95% Confidence Limits)	
<u>Intact Rats:</u>		
Aspirin	141	(67 - 297)
NC-1140	63	(28 - 138)
Phenylbutazone	15	(9 - 25)
Hydrocortisone	2.3	(0.6 - 8.7)
Acetate		
Indomethacin	0.31	(0.15 - 0.62)
Dexamethasone	0.28	(0.08 - 0.93)
<u>Adrenalectomized Rats:</u>		
NC-1140	97	(54 - 175)
Phenylbutazone	13	(5 - 33)
Indomethacin	3.9	(2.2 - 6.8)

E. Thermal Edema

Inhibition of thermally-induced edema was studied and adapted from the method of Rocha e Silva et al., *Med. Exp.* 3: 371 (1960). The drugs were administered orally to rats 30 minutes prior to immersion of the left hind paw in water at 55°C. for 30 seconds. The volume

of resultant edema was measured 1 and 4 hours after immersion.

Table 5

Drug	Oral Dose (mg./kg.)	1 hour		4 hours	
		ml. edema	% Inhibition	ml. edema	% Inhibition
Methylcellulose (controls)		1.44	—	1.60	—
Aspirin	100	1.00	31	1.57	2
NC-1140	100	1.11	23	1.64	0
Indomethacin	5	1.36	6	1.69	0

With the experimental method used it appears that both aspirin and NC-1140 were capable of delaying the onset of thermally-induced edema (1 hour) but did not prevent or inhibit the eventual massive swelling of the paw (4 hours). Indomethacin did not appear effective in inhibiting edema at either time after paw immersion.

F. Freund Adjuvant Studies (polyarthritis)

NC-1140 was utilized to combat the arthriticlike syndrome produced by injection of *Mycobacterium butyricum* (Freund's adjuvant).

1. Procedure

a. Four groups of 10 rats each were used.

Group 1 — These rats received no adjuvant injection and were orally dosed daily with the methylcellulose suspending agent. These control animals served to show the increase in paw size through normal body growth over the 31-day experimental period.

Group 2 — This group was injected in the tail with the adjuvant and orally dosed daily with methylcellulose. The purpose of this group was to show the progress of the arthritic state without an attempt to alter the syndrome.

Group 3 — These animals received the adjuvant injection on day 1 and were dosed orally with methylcellulose for the first 14 days of the experiment. On day 15, the animals were dosed orally with NC-1140 (25 mg/kg.) and were continued on this regime for the remaining 15 days. This treatment was an attempt to reverse or arrest the mechanisms responsible for producing the arthritic syndrome which were postulated to become evident at this point in the experiment.

Group 4 — This group was injected with the adjuvant on day 1 and were dosed orally with 25 mg/kg/day of NC-1140 for 30 days. This group represented an attempt to prevent the development of the arthritic syndrome.

Dorsal-ventral measurement of the hind paws and lateral measurements of the tibiotarsal joints were made with precision calipers on days 1, 15 and 31. Increased thickness of these areas over the nonadjuvant, no drug controls (Group 1) was considered a manifestation of the polyarthritic syndrome. In addition, visual inspection was made on the final day for the appearance of secondary lesions on the tail and skin surface of the paws. Other parameters measured on the final day were body weight gain, adrenal gland weights, thymus gland weights and gross inspection of the stomach linings for possible ulcerogenesis.

2. Results

FIG. 1 illustrates the results obtained with the two measurements of paw and joint thickness. On day 1 the thickness of both the dorso-ventral and tibiotarsal areas showed little inter-group deviation indicating similar base line values for both of these parameters. By day 15 there were no significant changes from normal growth indicating no evidence for the onset of the arthritic state. By day 31, however, the measurements of paw and joint thickness in Group 2 (adjuvant and no drug) were significantly ($P \leq .05$) higher than Group 1 (no adjuvant and no drug) indicating that swelling did occur. Measurements in Groups 3 and 4 (receiving NC-1140) were significantly lower than Group 2, indicating that the drug was showing an effect in both arresting and inhibiting the arthritic-like condition. No internal toxicity was observed.

EXAMPLE 3

Analgesic Activity of NC-1140

A. Pressure-Pain Method

Intraplantar injection of brewer's yeast in the hind paw of rats causes an inflammation which increases the sensitivity to pain. This increased sensitivity is susceptible to modification by known analgesic agents. The procedure used is based upon the method described by Randall and Selitto, Arch. Int. Pharmacodyn. 111: 409 (1957). Rats were injected in the left hind paw with 0.1 ml. of a 20 percent brewer's yeast suspension. One hour later the drugs were administered orally via stomach tube. The pain threshold was measured one hour after drug administration by applying a steadily increasing pressure of 16 grams/second to the inflamed paw. The end point (pain threshold) was defined as the pressure necessary to cause the animal to struggle and/or vocalize.

Effective analgesic doses were obtained by determining the amount of drug required to cause a 50 percent increase in the mean pain threshold over that of parallel groups of control animals. The following values were obtained:

Table 6

Analgesic Activity of Anti-Inflammatory Agents (Pressure-Pain Method)	
Drug	Analgesic Dose (mg./kg.)
Aspirin	185
NC-1140	72
Phenylbutazone	8.2
Indomethacin	1.1

Results obtained after several individual doses of the above agents are given in FIG. 2.

B. Anti-Writhing

Intraperitoneal injection of 0.2 ml. of 0.02 percent phenyl-p-quinone (P.P.Q.) in mice causes an acute abdominal pain which is characterized by numerous writhing episodes (contraction and torsion of the abdomen). The method used is a modification of the procedure reported by Vander Wende et al., Fed. Proc. 15: 494 (1956). Mice were administered the drug orally thirty minutes prior to the intraperitoneal injection of P.P.Q. Peak incidence of writhing occurs 5 minutes after injection of the irritant. At this time, the animals

are observed for a period of 3 minutes and the number of distinct writhing episodes are counted.

ED_{50} values were determined for aspirin, NC-1140, phenylbutazone, and indomethacin. (The ED_{50} is defined as the dose necessary to reduce the total number of writhes by 50 percent of controls).

Table 7

Anti-Writhing Activity of Anti-Inflammatory Agents	
Drug	ED_{50} vs. Writhing (mg./kg.)
Aspirin	41
NC-1140	20
Phenylbutazone	49
Indomethacin	0.44

C. Rat Tail-Flick

The method of D'Amour and Smith, J. Pharmacol. Exptl. Therap. 72: 74 (1941) was adapted as an adjunct to the study of the analgesic properties of drugs. Briefly, the tails of rats are placed in an apparatus which automatically initiates a time mechanism and starts a heating coil which transmits a painful stimulus to the ventral surface of the tail. At the end point, the animal "flicks" its tail from the apparatus. Measurements are made either $\frac{1}{2}$ and 1 hour post drug or one and 2 hours after drug administration, and averaged. "Analgesia" may be considered as a significant increase in the latency of pain perception and/or reaction time. The method is effective in detecting analgesic properties of the narcotic class of drugs (morphine, codeine, meperidine, etc.). Non-narcotic analgesics (aspirin, phenylbutazone, indomethacin, etc.) are not usually detected by this procedure. The test, therefore, may be used to differentiate between possible narcotic and non-narcotic analgesic activity. A doubling of the reaction time over control animals (no drug) may be considered significant. The following results were obtained with selected oral doses of representative narcotic analgesics and with high doses of certain non-narcotic analgesics.

Table 8

Effect of Various Analgesics on the Rat Tail-Flick Procedure		
Drug	Oral Dose (mg./kg.)	Average Response Time (seconds)
Methylcellulose (controls)	—	3.5
Morphine	32	7.0
Codeine	80	11.8
Meperidine	32	9.2
		Narcotic Class (all significantly active)
Aspirin	500	3.4
NC-1140	400	4.2
Phenylbutazone	160	5.6
Indomethacin	16	2.9
		Non-Narcotic Class (none significantly active)

Thus, NC-1140 appears similar to aspirin and other related non-narcotic analgesics.

EXAMPLE 4

Anti-Secretory Properties of NC-1140

The purpose of these experiments was to ascertain whether NC-1140 stimulated gastric secretion or caused significant changes in either free or total acid

content of gastric juices. Unusually high fluid volume or stimulation of acid secretion would be indicative of possible ulcerogenic properties.

The stomachs of rats were ligated at the pylorus (Shay rat procedure) immediately followed by an intraperitoneal injection of either NC-1140 (200 mg./kg.), aspirin (200 mg./kg.), or 0.25 percent methylcellulose (controls). Four hours later the animals were sacrificed, the stomachs removed and the total volume of fluid was measured. In addition, both free and total acid content of the gastric juices were determined.

Table 9

Anti-Secretory Activity of NC-1140 I.P. as Compared with Aspirin			
Treatment (I.P.)	Total Fluid Volume (ml.)	Acid Content (mg./ml. HCl)	
		Free	Total
Methylcellulose (controls)	4.5	3.0	3.7
Aspirin (200 mg./kg.)	4.4	1.3	2.2
NC-1140 (200 mg./kg.)	2.4	1.0	2.5

5

15

20

25

Because NC-1140 showed anti-secretory properties following both oral and intraperitoneal administration, additional studies were performed to compare this compound with several standard reference agents having known anti-inflammatory or anti-secretory activity. In these experiments, the stomachs of rats (fasted 48 hours) were ligated at the pylorus, followed immediately by the subcutaneous injection of various dose levels of the selected drugs. After 4 hours the animals were sacrificed and the total liquid volume, free and total acid content, and pH of the gastric juices were measured.

Table 10

Anti-Secretory Activity of NC-1140 Orally		
Treatment (Oral)	Total Fluid Volume (ml.)	% Reduction from control
Methylcellulose (control)	3.4	—
NC-1140 (100 mg./kg.)	1.9	44
NC-1140 (200 mg./kg.)	1.3	62

Table 11

Drug	S.C. Dose (mg./kg.)	No. of rats	Liquid Volume (ml.)	Acid Content (mg/ml HCl)		
				Free	Total	pH
Methylcellulose (controls)	53	4.3	3.9	5.1	1.44	
NC-1140	12.5	8	2.7 ⁽⁻⁾	2.8 ⁽⁻⁾	4.1 ⁽⁻⁾	1.52 ⁽⁺⁾
	25	8	2.6 ⁽⁻⁾	2.9 ⁽⁻⁾	4.3 ⁽⁻⁾	1.50
	50	8	1.3 ⁽⁻⁾	1.6 ⁽⁻⁾	3.6 ⁽⁻⁾	1.56 ⁽⁺⁾
Phenylbutazone	12.5	8	3.9	4.6	5.4	1.50
	25	8	4.3	4.7 ⁽⁺⁾	5.6	1.46
	50	8	3.3	4.7 ⁽⁺⁾	5.4	1.45
Aspirin	12.5	7	4.0	4.8 ⁽⁺⁾	6.1 ⁽⁺⁾	1.46
	25	7	3.4	4.4	5.9 ⁽⁺⁾	1.44
	50	7	3.6	4.1	5.6	1.43
Indomethacin	1.25	8	4.8	4.5	5.5	1.47
	2.5	8	4.1	3.1	4.9	1.43
	5	8	3.3	3.7	5.1	1.47
Dimenhydrinate (Dramamine)	12.5	8	4.5	4.3	5.4	1.45
	25	8	3.5	4.0	4.9	1.42
	50	8	2.6 ⁽⁻⁾	3.6	4.5 ⁽⁻⁾	1.50
Propantheline (Pro-Banthine)	0.05	8	3.4	3.3	4.9	1.37
	0.1	8	2.6 ⁽⁻⁾	3.5	5.1	1.37
	0.2	8	1.6 ⁽⁻⁾	3.7	4.7	1.55 ⁽⁺⁾
Trihexyphenidyl (Artane)	12.5	8	2.9 ⁽⁻⁾	3.8	4.8	1.49
	25	8	2.5 ⁽⁻⁾	3.5	4.4 ⁽⁻⁾	1.59 ⁽⁺⁾
	50	8	1.5 ⁽⁻⁾	3.3	3.8 ⁽⁻⁾	1.63 ⁽⁺⁾

⁽⁻⁾ = Significant reduction ($P \leq .01$) from mean control value

⁽⁺⁾ = Significant increase ($P \leq .01$) from mean control value

Based upon these data it appeared that NC-1140 was not only devoid of gastric secretion stimulating properties but caused a marked reduction (47 percent) in total fluid volume. Aspirin was inactive in this respect. In addition, both NC-1140 and aspirin caused reductions in both free and total acid content of the gastric juices.

The indication that NC-1140 possessed antisecretory properties stimulated a similar study to determine if anti-secretory activity was also evident after oral administration. The identical experimental procedure was repeated, with the exception that NC-1140 was administered orally one hour prior to ligation.

55

Thus, NC-1140 shows marked anti-secretory activity by three routes of administration (p.o., i.p., and s.c.). Phenylbutazone, aspirin, and indomethacin fail to significantly reduce gastric secretions. In addition, phenylbutazone and aspirin appear to increase the free and/or total acid content of the gastric juices following subcutaneous injection, while NC-1140 shows marked reductions in these parameters. The pH of the gastric juices was also significantly increased (buffering action) by NC-1140. This activity was observed with propantheline and trihexyphenidyl, two drugs in current use having therapeutic indications similar to atropine.

60

13
EXAMPLE 5

Toxicological Evaluation of NC-1140

A. Mortality

Comparative determination of acute (48 hour) and delayed (5 day) lethality after single doses in rats and mice with NC-1140 and other anti-inflammatory agents gave the following data for the 50 percent lethal dose (LD_{50}).

10

Table 12

Drug	Comparative Determination of Acute and Delayed Lethality							
	Oral (LD_{50}) (mg./kg.)		I.P. (LD_{50}) (mg./kg.)		Rats		Mice	
	48 hr.	5 Day	48 hr.	5 Day	48 hr.	5 Day	48 hr.	5 Day
NC-1140	1497	1368	1707	1531	487	487	616	440
Aspirin	1857	1857	>1900	>1900	1129	801	352	294
Phenylbutazone	618	599	1078	1078	264	212	283	277
Indomethacin	>240	17	>160	45	>100	39	>80	32

Following single oral administration to both rats and mice, NC-1140 appears reasonably free of toxicity. Via oral or intraperitoneal administration in rats or mice, the agent appears comparably non-toxic or safer than the other reference agents studied. Unlike indomethacin, NC-1140 does not cause marked incidence of delayed (5 day) deaths.

B. Therapeutic Safety Index

Calculation of the therapeutic index, defined as the value derived by dividing the 5 day rat oral LD_{50} value by the oral ED_{50} value against carrageenin edema, reveals the following:

Table 13

Drug	Oral Therapeutic Indices		Therapeutic Index
	Rats	Mice	
NC-1140	65		
Phenylbutazone	20		
Aspirin	8.3		
Indomethacin	7.1		

Thus, NC-1140 has a safety margin which is over 3 times that of phenylbutazone and 8 to 9 times that of aspirin and indomethacin.

EXAMPLE 6

Using the procedure set forth in Example 2A, the anti-inflammatory activity of a number of s-triazolo-[3,4-a]-isoquinoline compounds was determined. The results are set forth in the following table.

Table 14

Compound	Anti-inflammatory Activity Determined by Carrageenin-induced Edema Method		ED_{50} mg./kg.
		ED_{50} mg./kg.	
6-chloro-s-triazolo-[3,4-a]-isoquinoline	approx.	20	
3-(N-morpholinylmethyl)-s-triazolo-[3,4-a]-isoquinoline dihydrochloride	approx.	100	
7-nitro-s-triazolo-[3,4-a]-isoquinoline		62	
6-methyl-s-triazolo-[3,4-a]-isoquinoline		44	
6-cyano-s-triazolo-[3,4-a]-isoquinoline		107	
6-carbamido-s-triazolo-[3,4-a]-isoquinoline	approx.	30	
6-bromo-s-triazolo-[3,4-a]-isoquinoline		27.5	

14
Table 14—Continued

Compound	Anti-inflammatory Activity Determined by Carrageenin-induced Edema Method	
		ED_{50} mg./kg.
6-methoxy-s-triazolo-[3,4-a]-isoquinoline		18
3-chloro-s-triazolo-[3,4-a]-isoquinoline	approx.	60
3,6-dichloro-s-triazolo-[3,4-a]-isoquinoline	approx.	60

10

25	3-styryl-s-triazolo-[3,4-a]-isoquinoline hydrochloride	approx.	160
	3-methylthio-s-triazolo-[3,4-a]-isoquinoline		31
30	3-methyl-6-chloro-s-triazolo-[3,4-a]-isoquinoline		78

40	3-oxo-s-triazolo-[3,4-a]-isoquinoline	approx.	43
	"3-trifluoromethyl-s-triazolo-[3,4-a]-isoquinoline hydrochloride 34".		

EXAMPLE 7

Using the procedure set forth in Example 4, the anti-secretory activity of a number of s-triazolo-[3,4-a]-isoquinoline compounds was determined. The results are set forth in the following table.

Table 15

50	Compound	Anti-secretory Activity Reduction (%)*	
	6-chloro-s-triazolo-[3,4-a]-isoquinoline	61%	
	7-nitro-s-triazolo-[3,4-a]-isoquinoline	40	
55	6-methyl-s-triazolo-[3,4-a]-isoquinoline	27	
	6-bromo-s-triazolo-[3,4-a]-isoquinoline	approx. 50 (at 30 mg./kg.)	
	6-methoxy-s-triazolo-[3,4-a]-isoquinoline	26	
	3-methylthio-s-triazolo-[3,4-a]-isoquinoline	49	
60	3-ethylthio-s-triazolo-[3,4-a]-isoquinoline	40	
	8-methoxy-s-triazolo-[3,4-a]-isoquinoline	75	
	3-methyl-6-chloro-s-triazolo-[3,4-a]-isoquinoline	71	

65 * % Reduction of gastric secretion (ml./100 gm.) after subcutaneous administration to fasting rats (at 50 mg./kg. unless otherwise indicated).

In view of the above, it will be seen that the several objects of the invention are achieved and other advantageous results attained.

As various changes could be made in the above methods without departing from the scope of the invention, it is intended that all matter contained in the above description or shown in the accompanying drawings shall be interpreted as illustrative and not in a limiting sense.

What is claimed is:

1. A method of reducing inflammation in a mammal having such a disorder which comprises administering to said mammal an amount, sufficient to exert an anti-inflammatory effect, of a compound selected from the group consisting of 3-trifluoromethyl-s-triazolo-[3,4-a]-isoquinoline, 3-(N-morpholinylmethyl)-s-triazolo-[3,4-a]-isoquinoline, 5-chloro-s-triazolo-[3,4-a]-isoquinoline, 7-nitro-s-triazolo-[3,4-a]-isoquinoline, 6-cyano-s-triazolo-[3,4-a]-isoquinoline, 6-methoxy-s-triazolo-[3,4-a]-isoquinoline, 7-nitro-3-trifluoromethyl-s-triazolo-[3,4-a]-isoquinoline, 3,6-dichloro-s-triazolo-[3,4-a]-isoquinoline, 3-styryl-s-triazolo-[3,4-a]-isoquinoline, 3-methylthio-s-triazolo-[3,4-a]-isoquinoline, 3-ethylthio-s-triazolo-[3,4-a]-isoquinoline, 8-methoxy-s-triazolo-[3,4-a]-isoquinoline, 3-phenyl-s-triazolo-[3,4-a]-isoquinoline, s-triazolo-[3,4-a]-isoquinoline, 3-oxo-s-triazolo-[3,4-a]-isoquinoline, 3-thioxo-s-triazolo-[3,4-a]-isoquinoline, a 3-lower alkyl-s-triazolo-[3,4-a]-isoquinoline, a 3-lower alkyl-6-halo-s-triazolo-[3,4-a]-isoquinoline, a 3-halo-s-triazolo-[3,4-a]-isoquinoline, a 6-halo-s-triazolo-[3,4-a]-isoquinoline, a 7-halo-s-triazolo-[3,4-a]-isoquinoline, 3-(N-morpholinylmethyl)-s-triazolo-[3,4-a]-isoquinoline

30

dihydrochloride, 3styryl-s-triazolo-[3,4-a]-isoquinoline hydrochloride and 3-trifluoromethyl-s-triazolo-[3,4-a]-isoquinoline hydrochloride.

2. The method of claim 1 wherein said compound is 3-trifluoromethyl-s-triazolo-[3,4-a]-isoquinoline.
3. The method of claim 1 wherein said compound is 6-chloro-s-triazolo-[3,4-a]-isoquinoline.
4. The method of claim 1 wherein said compound is 7-nitro-s-triazolo-[3,4-a]-isoquinoline.
5. The method of claim 1 wherein said compound is 6-bromo-s-triazolo-[3,4-a]-isoquinoline.
6. The method of claim 1 wherein said compound is 6-methoxy-s-triazolo-[3,4-a]-isoquinoline.
7. The method of claim 1 wherein said compound is 3-chloro-s-triazolo-[3,4-a]-isoquinoline.
8. The method of claim 1 wherein said compound is 3,6-dichloro-s-triazolo-[3,4-a]-isoquinoline.
9. The method of claim 1 wherein said compound is 3-methylthio-s-triazolo-[3,4-a]-isoquinoline.
10. The method of claim 1 wherein said compound is 8-methoxy-s-triazolo-[3,4-a]-isoquinoline.
11. The method of claim 1 wherein said compound is 7-bromo-s-triazolo-[3,4-a]-isoquinoline.
12. The method of claim 1 wherein said compound is s-triazolo-[3,4-a]-isoquinoline.
13. The method of claim 1 wherein said compound is 3-oxo-s-triazolo-[3,4-a]-isoquinoline.
